UNITED STATES PATENT OFFICE

FRANK L. DIETZ, OF SEATTLE, WASHINGTON, ASSIGNOR OF ONE-HALF TO EDWIN H. LUKE, OF SEATTLE, WASHINGTON, AND ONE-HALF TO NORTH PACIFIC CEDAR PRODUCTS CORPORATION, OF SEATTLE, WASHINGTON, A CORPORATION OF WASHINGTON

HAND SPLIT TAPERED SHAKE

Application filed April 18, 1928, Serial No. 270,956. Renewed September 30, 1930.

My invention relates to split shakes, and especially to shakes split out according to the method disclosed in my prior Patent No. 1,663,905, which have two naturally split 5 faces, and which taper from butt to tip.

Hand split shakes, made of high quality vertical grain western red cedar and like woods, have been used in increasing numbers where it is desired to add a rustic touch to a 10 house. Such shakes may be used either on the side walls, or on the roof. However, in some instances, the owners of houses on which such shakes have been put, complain that the shakes are too uniform, that their 15 surface is too smooth and without contrasts, and that they have not the rustic appearance desired, due, primarily, to the fact that the cedar is of such quality (as it must be to make from it the large shakes) that it splits too 20 evenly and smoothly, and there is not sufficient break in the surface of the shakes. They appear almost machine-made in their sameness. Though one is conscious of it when close to the side walls of a house covered with 25 split shakes, this uniformity is especially noticeable from a distance, where the slight corrugations and channels, due to the vagaries of the grain, are not visible, and when such a roof is viewed from below, and nearly 30 in the plane of the roof, when the butts are most prominent. Being formed with an ordinary frow, which forms two straight, parallel butt edges, these butts appear quite as straight and "machine-made" as the butts of 35 ordinary sawed shingles, and lay quite as tightly. This tends to produce an altogether uniform appearance, which is not consistent with the rusticity which such owners have 40 expected, and desire.

As has been stated, the cedar, from which such shakes must be split, must be of the highest quality; the grain must be perfect, for wavy-grained wood cannot be used satisfactorily for the manufacture of such shakes, for then the tip thickness in particular, cannot be controlled. It follows, then, that when such wood is split it will split very nearly perfectly to a plane, and there will be little in the 45 way of angled or inclined surfaces to catch

the eye, or to reflect light, and to give the effect of a broken surface.

Accordingly, it is my object in the present invention, to produce a shake which has a surface which produces the appearance of being quite irregular, and which is in fact 55 exaggeratedly rigid, or corrugated, yet to form it of the same high quality wood. It is, of course, a further object to control the corrugations in such a manner that, though 60 appearing quite irregular, they are in fact all within a common plane, at least the upper portions of the principal ridges, so that succeeding courses can be laid sufficiently tight 65 to prevent any possibility of leakage, and without the possibility of the shakes in these succeeding courses being cocked to one side or at an angle to the general plane of the course, and to maintain the required thinness of the tip. 70

Associated with these objects, it is a further object to provide a butt edge, at least the edge of the butt which is to be uppermost, which is waved to give the impression of irregularity when viewed from below, that is, 75 when the shake is viewed end on.

A further object is the provision of such a shake, which has longitudinal channels for drainage which, by virtue of being larger than those ordinarily and naturally provided, will tend better to accumulate the water 80 in large drops and thus facilitate and assist in its draining off.

A further object is the provision of a frow whereby such shakes as have been described 85 may be split out so that the shakes can be thus produced at one operation, and require no further operation upon them.

In this specification I shall employ the term "shake" to mean a board having at least 90 one, and preferably two faces, which are naturally split from the block.

My invention comprises the novel shake, and the novel frow, for splitting the same, as 95 shown in the accompanying drawings, described in the specification, and particularly defined by the claims terminating the same.

In the accompanying drawings I have shown a shake, such as would be split by the process of my patent referred to above, and 100

the frow for making this shake, both in typical forms to illustrate the principle of the invention.

Figure 1 is a perspective view of the frow, which I intend to employ in the manufacture of my shakes.

Figure 2 is a perspective view showing, to a larger scale, the edge of the frow.

Figure 3 is a perspective view of a shake made with such a frow.

Figure 4 is a plan view and Figure 5 a side elevation, illustrating the manner of using such a frow.

Figures 6 and 7 are views similar to Figures 4 and 5, illustrating further the manner of using such a frow.

My invention is largely understandable from an inspection of the drawings. However, it should be pointed out that with the frow 5, having its entering edge 50 provided with a plurality of corrugations, that is to say, waved as seen in edge view, and having a broadened back 51, or like means to permit it to be struck and driven into a block, it is a simple matter to cut from a block, as 2, a plurality of shakes which will taper from butt to tip, according to the method disclosed in my former patent. This is illustrated in Figures 4, 5, 6 and 7, wherein the block 2 is shown in Figures 4 and 5 with one end, 25, uppermost, and the other end, 26, resting upon the ground or other suitable support. The frow 5 is now placed in position on the top 25, inward from the edge 21 of the block a distance equal to the desired butt thickness, and struck to enter the block and to define a plane of cleavage at 20. This plane of cleavage gradually tapers towards the edge 22 of the block to define a thinner tip. Ordinarily such blocks are split from larger bolts, and hence the surface 23 of the first shake off of a block will be split, but will not be exaggeratedly corrugated. The inner surface defined by the plane of cleavage 20, however, will be so corrugated, as will be both surfaces of succeeding shakes.

After taking off the first shake in this manner, the block is reversed end for end, the end 26 being now uppermost, as seen in Figures 6 and 7, the frow again entered along the plane of cleavage 20', set back from the edge 23 by a distance equal to the butt thickness now desired in the second shake, and a second shake is taken off. By repeating this process, reversing the block end for end each time, shakes will be taken off of the block which have both surfaces exaggeratedly ridged, or corrugated, and the butt edges of which are irregular or waved, rather than straight lines, such as the edge 21, (see Figure 4).

Such a shake is seen in Figure 3. Its edge 23 corresponds to the edge 23 of the second shake off of the block 2 (see Figures 6 and 7). Its edge 20' corresponds to the entering edge

at the plane of cleavage, the edge 23' at the tip of the shake represents the termination of the plane of cleavage at the bottom end of the block, after the second shake has been taken off.

It will be noted how these several edges are waved, the line 20, being formed by the frow, corresponds quite closely to the irregularities of the edge 50 of the frow. The edge 23', which is formed merely by a continuation of the splitting along the plane of cleavage, and not by any cutting action, still retains the irregularities of the edge 20', although there is some tendency for the exaggerated ridges to run out towards the tip end of a shake, especially when such a shake is of 37" length. This is not undesirable, however, but in fact assists in the laying of the shakes so that they will fit tightly one upon another in the manner of sawed shingles. Otherwise the ridges, as for example, the ridge R and the ridge R' are distinct throughout the length of the shingle, and afford a pleasing break to the sameness of surface which would result from the use of an ordinary straight edged frow. By employing a long frow, and by placing the frow differently in the several shakes taken off of a block, the surface may be varied in different ways by different arrangements of the ridges, and in this manner a wide variety of surface forms may come from a single block and from a single frow. This prevents any appearance of sameness or of machine manufacture, which is a characteristic especially of imitation shakes made by grooving sawed shingles.

What I claim as my invention is:—

1. A shake tapered from its butt to its tip, the two faces being naturally split, and with the natural corrugations exaggerated.

2. A shake tapering from butt to tip, the two faces being naturally split, the upper face having the natural corrugations exaggerated at its butt end, and tending to run out to a common plane towards its tip.

3. A shake tapering from butt to tip, the two faces being naturally split, the upper face having the natural corrugations exaggerated at its butt end, and tending to run out to a common plane towards its tip, and the under surface having like exaggerated corrugations commencing at its tip end, and tending to run out at the butt.

Signed at Seattle, King County, Washington, this 11th day of April, 1928.

FRANK L. DIETZ.
